**METERING PUMP SUITABLE FOR USE AS A
FUEL INJECTOR PUMP**

Theo Werner Schettler, Ermelo, Transvaal, Republic of South Africa, assignor to T. W. Schettler (Proprietary) Limited, Ermelo, Transvaal, Republic of South Africa

Filed Apr. 8, 1963, Ser. No. 271,331

Claims priority, application Republic of South Africa, Apr. 10, 1962, 62/1,513
15 Claims. (Cl. 123—139)

This invention relates to pumps of the kind suitable for pumping liquids in metered quantities, such as for example fuel injection pumps for internal combustion engines.

According to the invention, a pump of the kind referred to comprises a stator and rotor assembly, the rotor having at least one port directed outwardly, an axial inlet passage connected with the or each port in the rotor, and at least one transverse bore connected to the inlet passage and having an inlet opening into it; at least one plunger member reciprocable within the bore and being biased outwardly; a cam sleeve within the stator and connected to it, and around the rotor and slidably co-axially with it and having at least one cam lobe on its inner periphery adapted to engage with the plunger, the cam lobe having a face which slopes relative to the sleeve axis; cam sleeve bias means for biasing the cam sleeve axially to a position in which that part of the cam lobe having the highest lift engages with the plunger member; cam sleeve position governing means for governing the position of the cam sleeve axially relative to the rotor against the action of the bias means; and drive connecting means for receiving rotary power applied to the rotor; the stator having one or more ports with which the rotor port is adapted to register during rotation of the rotor within the stator; the arrangement being such that when the rotor rotates within the stator, the plunger reciprocates within its bore under the action of the cam lobe and the bias means and thereby performs a pumping action, the rotor and stator ports being arranged to register when the plunger is on its delivery stroke.

The cam sleeve may be arcuately displaceable about its axis relative to the stator. Arcuate and axial displacement may take place simultaneously, by means of a helical slot or groove provided in the sleeve or stator and a co-operating keying element or tongue provided on the stator or sleeve, as the case may be. The sleeve is biased conveniently to an initial axial position within the stator by means of the bias means which may be a spring, and displacement of the sleeve takes place by the cam sleeve position governing means whose displacement is conveniently proportional to variations in speed of the rotor.

The cam sleeve position governing means may comprise governor pressure pump means connected drivingly to the rotor or driven independently at a speed proportional to rotor speed, or such that its delivery pressure is proportional to rotor speed. The governor pressure pump means may be arranged to deliver fluid under pressure into an annular pressure cavity defined within the stator between the cam sleeve, rotor, and stator; the cam sleeve being axially displaceable within the stator under the action of fluid pressure. The pump means may be a gear pump comprising a toothed gear wheel arranged eccen-

2

trically to the rotor axis, and a driving gear co-axial with the axis. If desired, a plurality of toothed gear wheels may be arranged, disposed around the gear coaxial with the axis, and eccentrically to the rotor axis, the several gear pumps so formed constituting the governor pressure pump. There may be provided delivery passages leading from the several gear pumps constituting the governor pump to the annular pressure cavity; and fluid flow control means in the various delivery passages to control the flow of fluid into the annular pressure cavity such that flow takes place into the cavity from the various pumps at various predetermined pressures.

The suction of the pumps may be fed from a reservoir provided and delivery from the pumps may be connected to the annular pressure cavity defined between rotor, stator, and sleeve, such that increase of pressure of hydraulic fluid inside the cavity causes axial displacement of the sleeve against the action of the bias means to vary the stroke of the plunger by decreasing the throw or lift of the cam lobe relative to the plunger. The arrangement is such that the sleeve forms an annular plunger axially displaceable under the hydraulic pressure from the pump or pumps, the pressure being proportional to the speed of the pump(s) which in turn is proportional to rotor speed. Variations in pressure may be damped by a damper and excess pressure may be diverted by way of a relief valve provided.

The plunger or plungers may include balls, which may be arranged to ride in cages if desired, and the bore axis may be at right angles to the rotor axis and may intersect it. The port or ports in the stator may be connected to an injector or injectors of an internal combustion engine, the delivery from the ports taking place at timed intervals depending upon the speed of the engine.

In practice, the number of cam lobes and ports in the stator will be matched to the number of injectors to be fed, each port in the stator being in connection with an injector. A plurality of ports may be used but if desired, only one port may be provided in the rotor the port being adapted to come into register discretely in succession with a plurality of ports in the stator. The cam lobes may have varying shapes and lengths offering varying displacements and rates of displacement of the plungers.

Reference will now be made to the accompanying drawings, which show diagrammatically two examples of the invention, as applied to the fuel pump of a compression ignition engine.

In the drawings:

FIGURE 1 shows diagrammatically a longitudinal section of the invention;

FIGURE 2a shows a detail in part at II—II of the sleeve;

FIGURE 2b shows a section at IIb—IIb of FIGURE 2a;

FIGURE 3 shows diagrammatically a longitudinal section of another embodiment of the invention in one operative position;

FIGURE 4 shows a view similar to FIGURE 3 but at another longitudinal section;

FIGURE 5 shows an outside plan of the cam sleeve;

FIGURE 6 shows diagrammatically an axial section of a resilient connection between a bias member and an operating member; and

FIGURE 7 shows a part sectional side elevation of an over pressure relief valve.

Referring to FIGURES 1, 2a, and 2b of the drawings, reference numerals 10 refers to a stator comprising a shell 12 having a bore 14 within which rotor 16 is mounted to rotate co-axially with the stator. The rotor 16 has shaft 18 whereby rotary power may be applied to it. Cam sleeve position governing means in the form of gear pumps 20 and 22 are provided for pumping hydraulic fluid from a reservoir not shown. These pumps also act as fuel feed pumps and their operation will be more fully described hereafter.

The stator is provided with radial ports 24 which are adapted to register with the ports 26 in the rotor and are connected via passages 28, 30, and 32, to transverse bores 34 having plungers 36 biassed by springs 38. The plungers 36 are axially displaceable in the bores 34 by means of balls 40 which roll or slide along the inner face 42 of an annular cam ring 44 having one or more cam lobes 46, when the rotor 16 rotates within stator 12.

The cam ring 44 has a face 48 which defines an annular cavity 50 in association with rotor 16 and stator 10. The deliveries of the pumps 20 and 22 are connected for discharge into cavity 50, by means of threaded connection 52. The cam sleeve 44 is biassed to an initial position of maximum cam lobe lift by means of spring 54 disposed within cavity 56 charged under pressure with fluid (e.g. fuel oil) whose delivery is to be metered in small discrete quantities. Inlet passages 58 are provided in rotor 16, and connect bores 34 to cavity 56. This cavity 56 is charged via threaded connection 59.

Cam sleeve 44 is connected via helical grooves 45 and engaging keying elements or tongues 47 to stator 10 such that axial displacement of ring 44 in direction of arrow 60 will cause it to be displaced also arcuately about the rotor axis. In this way the cam lobes 46 may be advanced relative to the rotor 16, to secure earlier operation of the plungers 36 and consequently earlier delivery and charging of fuel into engine cylinders.

In operation, a liquid such as fuel oil is charged into cavity 56 via threaded connection 59, from one of the pumps 20, 22 or from an independent fuel pump not shown and at a pressure slightly above atmospheric.

Rotation of rotor 16 within stator 10 causes balls 40 to be cyclically displaced along bores 34 as they ride up and over cam lobes 46. Such cyclic displacements cause fuel to be drawn into bores 34. Inward displacement of plungers 36 causes the inlet passages 58 to be closed off and liquid in bores 34 to be subjected to pressure. If ports 26 and 24 are in register then a quantity of fuel oil will be delivered which is proportional to the displacement of a plunger 36 in its bore 34.

Ports 26 and 24 may be suitably matched and connected to various cylinders of an engine, each port 24 serving a different cylinder.

Shaft 18 is driven from the engine whose fuel is to be fed by the assembly, and is so geared and timed that it delivers fuel in discrete quantities at the proper time to the various cylinders. As the engine speeds up, so the delivery of hydraulic pumps 20, 22 increases proportionally to engine speed and the pressure in cavity 50 is balanced against the pressure of spring 54 and that of the fluid in cavity 56 (cam ring 44 in taking up a balanced position may be axially and arcuately displaced relative to the stator shell 12). The time of delivery of the plunger 36 is thereby advanced relative to the pistons in the cylinders of the engine by a determined amount and the quantity delivered is suitably varied, depending upon the degree of axial and arcuate displacement of the cam ring 44, and depending upon the speed and requirements of the engine. The cavity 50 may be provided with a bleed opening.

It will be apparent that the pumps 20, 22 may be separately driven if desired, and may be independent of rotor 16, as long as their delivery pressure is proportional to

the speed of the engine. It will also be apparent that the fuel pump may be independent as mentioned, but if desired it may form a single integral unit with the whole.

Referring now to FIGURES 3 and 4 of the drawings there is shown a fuel feed pump for an internal combustion engine. The construction is basically the same as that shown in FIGURE 1, but differs in the cam sleeve governing means, which comprises a composite gear pump having a centrally disposed gear wheel 150 fast with the rotor 16 and four circumferentially spaced toothed gear wheels having different numbers of teeth meshing with the central gear wheel 150. These pumps are arranged to deliver fluid at different pressures to cavity 50 and the manner in which they are connected to the fuel metering pump will be more fully described later. Two of the gear pumps are designated 20 and 22.

Inside cavity 56 there is provided an axially displaceable bias member 84 against which spring 54 is arranged to abut in urging cam sleeve 44 towards the position of maximum cam lobe lift relative to the plunger balls 40. The bias member has a co-axial stem 86 and biassing means 94 for connecting it operatively to an operating member 96. (See FIGURE 6 to be more fully described later.)

An over-pressure relief valve 88 is provided out of the cavity 56 via passage 89, and non-return inlet valves 90 are provided in the inlet passages 58 connecting the bores 34 to the cavity 56, which is fed with pressure fluid via passage 92 from one of the gear pumps constituting the governor pressure pump.

The embodiment of FIGURES 3 and 4 has a set of four bores 34 instead of two as shown in FIGURE 1.

FIGURE 5 shows an outside plan of sleeve 44 and in particular the tongue 47 for engaging with the groove 45 whereby the sleeve is arcuately displaced about its axis when it is axially displaced.

FIGURE 6 shows diagrammatically the resilient connection 85 between the stem 86 of the bias member 84, the connection comprising a socket 92, second bias means in the form of a spring 94, and connecting member 96 for connection to the fuel control, say, the accelerator of an internal combustion engine to the stem 86. The stem passes through a gland 87 in the stator.

Referring again to FIGURE 3, there is shown further a control valve generally indicated by reference numeral 100 and comprising a core 102, housed within a bore 104 in the stator, a sleeve 106 within the bore, and bias means in the form of a spring 108 urging the sleeve to an initial position. A passage 110 connects the delivery of one of the pumps, say pump 20 to the bore. The core 102 has an internal passage 112 adapted to register with holes 114 provided in sleeve 106. The holes 114 lead into an annular groove 116 around the sleeve, the groove being adapted to register with a passage 118 leading into cavity 50. At the other end of the bore there is provided a passage 120 leading from over-pressure relief valve 88 into the bore 104. A bleed passage 80 is provided out of cavity 50 back to the suction of one of the pumps.

Referring to FIGURE 4, another axial section is shown, showing another valve 88a similar to 88, and another control valve 100a similar to valve 100. The parts of valve 100a are numbered similarly to those of valve 100 but have suffixes a. The passage 110a is the delivery passage of another of the pumps comprising the composite pump and is arranged to come into operation at a higher delivery pressure.

Referring to FIGURE 4 there is shown a non-return valve 130 in a passage 81 leading from one of the governor pumps to the cavity 50. This valve 130 is preloaded thus ensuring that fluid is received from this particular pump only after a predetermined delivery pressure has been reached by that pump, i.e. after it has reached a predetermined speed. This valve will be adjusted to lift at a pressure, say corresponding to $x\%$ overspeed of the engine. Pressure will then be admitted into cavity 50

via passage 81, whereupon the pressure in the cavity 50 will increase and the sleeve 44 will be displaced fully against the action of the spring 54, i.e. into a position of minimum or no cam lift and thereby cutting out the operation of the engine.

In operation of the pump as a fuel pump for an internal combustion engine, the position of the cam sleeve 44 as shown in FIGURE 3 is that obtained at starting of the engine. The sleeve 44 is right in and the lift of the cam lobes 45 at this axial position of the cam sleeve is at a maximum and maximum quantities of fuel are also delivered to the cylinders of the engine when the rotor rotates. As soon as firing starts, the engine speeds up and one of the governor pumps delivers fluid into cavity 56 via passage 92. Pressure on this side of the sleeve will tend to displace it towards greater cam lift and therefore greater engine speed which would in turn result in greater pressure in the cavity 56. As soon as the pressure in the cavity 56 reaches a value determined by the setting of valve 88, it lifts and admits fluid under pressure via passage 120 into bore 104. Sleeve 106 is thereupon displaced axially against the action of spring 108 thereby placing delivery passage 110 in connection with cavity 50 via passage 112, holes 114, groove 116, and passage 118. One of the pumps will deliver at a high pressure into passage 110 and thence to cavity 50. The pressure in cavity 50 will therefore be balanced against the spring 54 and the pressure in cavity 56. Fluid is bled away from cavity 50 via bleed passage 80.

When the pressure in cavity 56 becomes too great valve 88 closes and shuts off the bore 104 from cavity 56. At this stage valve 88a lifts and allows pressure fluid from cavity 56 to displace sleeve 106a and so to bring a higher pressure pump into connection with the cavity 50, and so to take over the function of the pump previously in connection but now disconnected.

If it is required to speed up the engine then the control is operated so that the cam sleeve 44 moves to the right, thereby increasing the stroke of the plungers 34 and causing more fuel to be supplied to the engine thereby causing it to run faster. The sleeve will take up a new balanced position depending upon the spring pressure and upon the pressures in cavities 50 and 56. The axial displacement of the cam sleeve causes it to be displaced helically about its axis relative to the stator, by means of keying element or tongue 47 co-operating with groove 45, thus causing the sleeve to be advanced in relation to the rotor in accordance with the requirements of the engine. The pitch of the helix will depend upon the degree of advance required for the particular engine with which the pump is to be used.

Referring now to FIGURE 7, there is shown a detail of the relief valve 88. This valve comprises a valve closure member 160 seated in bore 162 in stator shell 12. The member 160 has a passage 164 adapted to register with passage 120 in stator shell 12, when displaced by fluid pressure in cavity 56 against the action of spring 166 around closure member stem 168. The stem 168 has a face 169 which is arranged to seat closably in seat 170 provided in nut 172 having a tubular stem 174 adapted to receive a banjo connection 176 which is held sealingly in position between gaskets 177 and 178 by nuts 172 and 179. The bore of the stem 174 communicates with the banjo connection 176 via openings 180. Lock nut 181 provides for locking nut 172 in position under predetermined tension of spring 166.

In operation, closure member 169 lifts under pressure from cavity 56 entering bore 162 by way of passage 89. Fluid pressure from cavity 56 will then be in communication with bore 104 via passage 120. Further displacement of member 160 under greater pressure will cause passage 164 to discharge into cavity 182 and thence to a reservoir or pump suction connection via banjo connection 176. If the pressure rises further then, face 169 seats against seat 176 and so closes off the delivery. This will

cause the pressure in cavity 56 to rise and will cause valves 88a and 100a to take over, for the next stage of operation.

The governor pump means therefore comprises four gear pumps, each having a pressure and capacity characteristic differing from the others. The one pump delivers continually into cavity 56, two pumps deliver in stages into cavity 50 via control valves 100 and 100a and the fourth pump only delivers into cavity 50 via valve 130 upon excess pressure due to overspeed.

If desired, the governor pump means may have one or more constituent pumps delivering via valves such as 100 and 100a, depending upon requirements. By suitable adjustment, the pumps may be arranged to take over at various pressures. If desired, the adjustment may be such that there is some overlap between valves of the type 88 and 88a, for the several pumps, such that the one is already opening before the other has closed off completely.

I claim:

1. A pump of the kind referred to which comprises a stator and rotor assembly, the rotor having at least one port directed outwardly, an axial inlet passage connected with the or each port in the rotor, and at least one transverse bore connected to the inlet passage and having an inlet opening into it; at least one plunger member reciprocable within the bore; plunger bias means biassing the plunger member outwardly; a cam sleeve within the stator and connected to it, and around the rotor and slideable co-axially with it and having at least one cam lobe on its inner periphery adapted to engage with the plunger, the cam lobe having a face which slopes relative to the sleeve axis, and the connection between the stator and cam sleeve comprising at least one helical groove and mating element; cam sleeve bias means for biassing the cam lob having the highest lift engages with the plunger member; cam sleeve position governing means for governing the position of the cam sleeve axially relative to the stator and rotor against the action of the cam sleeve bias beans; and drive connecting means for receiving rotary power applied to the rotor; the stator having at least one port with which the rotor port is adapted to register during rotation of the rotor within the stator; the arrangement being such that when the rotor rotates within the stator, the plunger reciprocates within its bore under the action of the cam lobe and the plunger bias means and thereby performs a pumping action, the rotor and stator ports being arranged to register when the plunger is on its delivery stroke, and the arrangement also being such that axial displacement of the cam sleeve relative to the stator and rotor by the cam sleeve position-governing means causes arcuate displacement of the cam sleeve about its axis relative to the stator thereby providing an advance and retard characteristic to the cam sleeve relative to the rotor.

2. A pump according to claim 1, in which backflow cut-off means is provided for the inlet opening into the axial inlet passage to prevent backflow through the inlet opening at the commencement of a pumping stroke of the plunger member.

3. A pump according to claim 2, in which the backflow cut-off means comprises a non-return inlet valve.

4. A pump of the kind referred to which comprises a stator and rotor assembly, the rotor having at least one port directed outwardly, an axial inlet passage connected with the or each port in the rotor, and at least one transverse bore connected to the inlet passage and having an inlet opening into it; at least one plunger member reciprocable within the bore; bias means biassing the plunger member outwardly; a cam sleeve within the stator and connected to it, and around the rotor and slideable co-axially with it; means defining an annular pressure cavity within the stator between the cam sleeve, rotor, and stator, the cam sleeve having at least one cam lobe on its inner periphery adapted to engage with the plunger,

and the cam lobe having a face which slopes relative to the sleeve axis; cam sleeve bias means for biasing the cam sleeve axially to a position in which that part of the cam lobe having the highest lift engages with the plunger member; cam sleeve position-governing means for governing the position of the cam sleeve axially relative to the stator and rotor against the action of the cam sleeve bias means, and comprising a governor pressure pump for delivering a fluid under pressure, and conduit means connecting the delivery of the pressure pump to the annular pressure cavity; drive connecting means for receiving rotary power applied to the rotor, the stator having one or more ports with which the rotor port is adapted to register during rotation of the rotor within the stator; the governor pressure pump comprising a gear-toothed sun wheel and a plurality of circumferentially spaced toothed wheels in mesh with the sun wheel thereby forming a plurality of separate gear pumps; there being provided delivery passages leading from the several gear pumps constituting the governor pump to the annular pressure cavity, and fluid control means in the various delivery passages to control the flow of fluid into the annular pressure cavity such that flow takes place into the cavity from the various pumps at various predetermined pressures, the arrangement being such that when the rotor rotates within the stator, the plunger reciprocates within its bore under the action of the cam lobe and the bias means and thereby performs a pumping action, the rotor and stator ports being arranged to register when the plunger is on its delivery stroke.

5. A pump according to claim 4 in which the circumferentially spaced toothed wheels in mesh with the sun wheel have differing numbers of teeth and are arranged to deliver fluid at different pressures at a particular speed of the sun wheel, in which fluid pressure of at least one of the pumps is arranged to assist the bias means against the action of fluid pressure in the annular pressure cavity, and in which the pressure from the pump assisting the bias means is arranged to control the operation of the fluid flow control means for directing fluid pressure flow 40 into the annular pressure cavity or for cutting it off.

6. A pump according to claim 5 in which a plurality of pumps are arranged to oppose the bias means, but to come into operation in stages at different pressures.

7. A pump according to claim 4 in which the cavity is provided with a bleed passage.

8. A pump according to claim 4, and suitable for connection as the fuel feed pump of an internal combustion engine, in which there is provided a further pump having a delivery connection to the cavity, a pressure relief valve in the passage and adapted to be set at a predetermined pressure corresponding to a predetermined speed of the engine; whereby generation of the predetermined pressure causes fluid to pass through the relief valve and into the cavity and there is cause displacement of the sleeve to the cam minimum lift condition, thereby preventing the speed of the engine exceeding the value corresponding to the predetermined pressure valve.

9. A pump of the kind referred to which comprises a stator and rotor assembly, the rotor having at least one port directed outwardly, an axial inlet passage connected with the or each port in the rotor, and at least one transverse bore connected to the inlet passage, and having an inlet opening into it; at least one plunger member reciprocable within the bore; bias means biasing the plunger member outwardly; a cam sleeve within the stator and connected to it, and around the rotor and slidable co-axially with it, and having at least one cam lobe on its inner periphery adapted to engage with the plunger, the cam lobe having a face which slopes relative to the sleeve axis; cam sleeve bias means for biasing the cam sleeve axially to a position in which that part of the cam lobe having the highest lift engages with the plunger member; a bias member within the stator and co-axial with it and axially slidable in it; positioning means for reg-

ulating the position of the bias member within the stator, the cam sleeve bias means being arranged to abut at one end against the bias member; cam sleeve position-governing means for governing the position of the cam sleeve axially relative to the rotor against the action of the cam sleeve bias means; drive connecting means for receiving rotary power applied to the rotor; the stator having one or more ports with which the rotor port is adapted to register during rotation of the rotor within the stator; the arrangement being such that when the rotor rotates within the stator, the plunger reciprocates within its bore under the action of the cam lobe and the bias means and thereby performs a pumping action, the rotor and stator ports being arranged to register when the plunger is on its delivery stroke.

10. A pump according to claim 9 in which the positioning means includes a stem projecting through a gland in the stator, and a resilient connection including second bias means for connecting the stem to the fuel control of an internal combustion engine, the second bias means being stiffer than the first bias means.

11. A pump of the kind referred to which comprises a stator and rotor assembly, the rotor having at least one port directed outwardly, an axial inlet passage connected with the or each port in the rotor and at least one transverse bore connected to the inlet passage and having an inlet opening into it; at least one plunger member reciprocable within the bore; bias means biasing the plunger member outwardly; a cam sleeve within the stator and connected to it, and around the rotor and slidable co-axially with it and having at least one cam lobe on its inner periphery adapted to engage with the plunger, the connection between the stator and cam sleeve being provided by at least one helical groove and mating element; cam sleeve bias means for biasing the cam sleeve axially; cam sleeve position-governing means for governing the position of the cam sleeve axially relative to the stator and rotor against the action of the cam sleeve bias means; and drive connecting means for receiving rotary power applied to the rotor; the stator having one or more ports with which the rotor part is adapted to register during rotation of the rotor within the stator; the arrangement being such that when the rotor rotates within the stator, the plunger reciprocates within its bore under the action of the cam lobe and bias means and thereby performs a pumping action, the rotor and stator ports being arranged to register when the plunger member is on its delivery stroke, and the arrangement being such that axial displacement of the cam sleeve relative to the stator and rotor by the cam sleeve position-governing means causes arcuate displacement of the cam sleeve about its axis relative to the stator thereby providing an advance and retard characteristic to the cam sleeve relative to the rotor.

12. A pump according to claim 11, including means defining an annular pressure cavity within the stator between the cam sleeve, rotor and stator; and in which the cam sleeve position-governing means comprises a governor pressure pump for delivering a fluid under pressure, and conduit means connecting the delivery of the pressure pump to the pressure cavity; the governor pressure pump comprising a gear toothed sun wheel and a plurality of circumferentially spaced toothed wheels in mesh with the sun wheel thereby forming a plurality of separate gear pumps; there being provided delivery passages leading from the several gear pumps constituting the governor pump to the annular pressure cavity, and fluid flow control means in the various delivery passages to control the flow of fluid into the annular pressure cavity such that flow takes place into the cavity from the various pumps at various predetermined pressures; whereby the governing of the axial position of the cam sleeve relative to the rotor can be controlled by the various fluid pressures from the governor pressure pump.

13. A pump according to claim 11, including a bias member within the stator co-axial therewith and slidable axially therein, and positioning means for regulating the position of the bias member in the stator, the cam sleeve bias means being arranged to abut at one end against the bias member. 5

14. A pump according to claim 11, including backflow cut-off means for the inlet opening into the axial inlet passage to prevent backflow through the inlet opening at the commencement of a pumping stroke of the plunger member. 10

15. A pump according to claim 14, in which the backflow cut-off means comprises a non-return inlet valve. 10
